United States Patent Office.

MARTIN L. SENDERLING, OF JERSEY CITY, NEW JERSEY.

Letters Patent No. 60,797, dated January 1, 1867.

IMPROVED APPARATUS FOR MIXING SUGAR.

The Schedule referred to in these Letters Patent and making part of the same.

TO ALL WHOM IT MAY CONCERN:

Be it known that I, MARTIN L. SENDERLING, of Jersey City, in the county of Hudson, and State of New Jersey, have invented a certain new and useful Improvement in Sugar-Mixing Apparatus, of which the following is a full, clear, and exact description, reference being had to the accompanying drawing, forming part of this specification, and in which—

Figure 1 represents a sectional elevation of an apparatus in illustration of my improvement.

Figure 2, a plan of a divided hopper, capable of being used in connection with said apparatus; and

Figure 3, a plan of the same apparatus, with the hopper removed.

Like letters indicate like parts throughout the several figures.

The nature of my invention consists in a novel process of mixing different grades or qualities of sugar by means of a wheel acting upon the principle of centrifugal force; also, in a novel construction of said wheel; likewise, in a combination of such device with a mill for crushing the lumps preparatory to the distribution or mixing of the sugar by the wheel; and finally, in a combination with the mixing-wheel or wheel and mill of a divided hopper for delivering to the same, by a common orifice, sugar of different grades or qualities.

Referring to the accompanying drawing, A represents a hopper divided into any number of suitable compartments, b, for feeding in to the apparatus, separately and distinct, sugar of different grades or qualities, but deliverable at a common orifice, c, on opening a slide, d. Though not absolutely necessary thus to introduce the sugars separate and distinct, as an undivided hopper may be used and the different grades of sugar be shovelled in by successive layers or promiscuously, such a divided hopper uniting in a common discharge is preferable, as the relative quantities of the different sugars are more readily determined and controlled, and a more general or equal mixture of them at the discharge effected. Beneath the delivery aperture, c, of the hopper is arranged a sugar-mill, of which B B are the rolls, suitably geared and rotated, and which serve to receive in between them the sugars as they are delivered from the hopper and to crush all lumps in the different sugars. Thus freed from lumps, the sugars are then in a condition to be distributed, scattered, and mixed by centrifugal force, which I find best adapted to the purpose, and which may be accomplished by any suitably constructed wheel, either of a horizontal or vertical character. I, however, prefer a wheel of horizontal arrangement, working on a vertical axis, situated on one side of the mill and rotated by suitable gear. Such an arrangement is represented in the drawing, in which the wheel is made-up of vanes, C, connected with a vertical shaft, e, and rotating as indicated by the arrow z. These vanes, C, are made of a fan or flaring shape from the axis towards the periphery, and have their faces set inclining upwardly in a backward direction, so that the sugars received upon them from the mill are restrained from falling or slipping off in the rear of them by the motion of the wheel, which acts as a centrifugal force to scatter, distribute, and mix the several grades of sugar received upon it.

What I claim as my invention, and desire to secure by Letters Patent, is—

1. The process, substantially as herein described, of mixing sugars through centrifugal force by means of a wheel receiving upon it sugars of different grades or qualities.
2. The mixing wheel acting by centrifugal force, constructed with vanes inclining on their faces upwardly in a backward direction in relation to the run of the wheel, essentially as specified.
3. The combination, with the centrifugal mixing-wheel, of a crushing-mill, arranged to deliver the crushed sugar directly upon said wheel, substantially as herein set forth.
4. The combination, of a divided hopper, crushing-mill, and centrifugal mixing-wheel, essentially as specified.

MARTIN L. SENDERLING.
